ELECTRIC AIR DIRECTOR

Herbert F. Bruns, 3520 Segovia St.,
Coral Gables, Fla. 33134

Filed Apr. 11, 1966, Ser. No. 1,835

Term of patent 7 years

(Cl. D62—4)

FIG. 1

FIG. 2

FIG. 3

FIG. 4

FIG. 5

FIG. 1 is a front elevation of an electric air director showing my new design.

FIG. 2 is a top plan view thereof.

FIG. 3 is a side elevation thereof.

FIG. 4 is a rear elevation thereof.

FIG. 5 is a bottom plan view thereof.

The side not shown is the same as that shown in FIG. 3. The dominant features of the design are shown in full lines.

I claim:

The ornamental design for an electric air director, as shown and described.
